UNITED STATES PATENT OFFICE

FRED M. REUTER, OF CHICAGO, ILLINOIS

BUILDING CONSTRUCTION

Application filed March 31, 1927. Serial No. 179,798.

In certain city neighborhoods one can usually find a number of old frame buildings adjacent to which buildings of a modern brick construction have been built, thereby 5 not only tending to give the older wooden buildings an antiquated and dilapidated appearance, but, furthermore, tending to depreciate the value of said old buildings.

In order to obviate the above conditions 10 to a considerable extent this invention relates to improvements in building construction and more particularly in improving the fronts of old frame buildings and the like by covering the front of a building with a 15 false front constructed of interfitting wooden face strips the exposed faces of which are covered with asphalt composition and have cemented or otherwise secured thereto strips of water proof roofing material in the shape 20 of the exposed surfaces of bricks to give the front of a building the appearance of a brick building of modern construction.

It is an object of this invention to provide 25 means whereby the walls of buildings may be given the appearance of brick walls by using improved interfitting strips of lumber having the exposed surfaces thereof covered with asphalt composition and having strips of water proof material cemented in the asphalt at spaced intervals to assume the appearance of a strip of bricks.

It is also an object of this invention to 30 provide a building construction of simplified and inexpensive construction adapted to be used as a covering for the walls of old buildings to give said walls the appearance of a modern brick structure.

It is a further object of this invention to 35 provide an improved building material with a false brick surface of water proof and fire proof material adapted to be used as an outer surfacing for the walls of buildings to give the buildings the appearance of brick structures.

40 It is furthermore an object of this invention to provide an improved method of reconstructing old frame buildings to have the appearance of brick buildings by removing portions of the walls of the old building and then covering said walls by false fronts con-

structed of boards having strips of roofing material or the like cemented thereon by means of an asphalt composition covering or the like.

It is an important object of this invention 55 to provide an improved building material of inexpensive construction adapted to be readily mounted in place to serve as a false brick covering for old buildings after the finishing moldings and trimmings have been removed 60 in order that the renovated building will have the appearance of a modern brick building of improved appearance, and, furthermore, tending to uphold the real estate value 65 of the same.

Other and further important objects of this invention will be apparent from the disclosures in the specification and the accompanying drawings.

This invention (in a preferred form) is 70 illustrated in the drawings and hereinafter more fully described.

On the drawings:

Figure 1 is a front elevation of an old building renovated in accordance with the 75 practice of this invention and with parts partly broken away to show the original construction as well as the improved construction.

Figure 2 is an enlarged fragmentary detail front view of a portion of the improved false front of the building.

Figure 3 is a transverse section taken on line III—III of Figure 2.

Figure 4 is an enlarged vertical detail 85 section through the front of the building and through one of the windows on line IV—IV of Figure 1.

Figure 5 is an enlarged fragmentary detail horizontal section taken on line V—V 90 of Figure 1.

As shown on the drawings:

The reference numeral 1 indicates the original wooden front of an old building having decorative window casings and moldings 2 as well as decorative wooden cornice moldings 3. In order to renovate or reconstruct the old building at a low cost in order 95 to give the front of the building the appearance of a modern brick structure, an 100

improved building material is provided as follows:

The outer projecting window rosettes and moldings 2 together with the decorative cornice molding 3 and the like are first removed from the front of the old building after which a plurality of wooden risers 4 are nailed or otherwise secured in vertical parallel relation across the front of the building.

In order to give the building the appearance of a brick structure a false front is secured to the risers 4. The improved front is of wooden construction made up of boards 5 having a groove 6 in one longitudinal edge thereof and a rib 7 on the opposite longitudinal edge or face. This construction permits the boards 5 to interfit with one another, as shown in Figure 3, with the rib 7 of one board projecting into the groove 6 of the adjacent board. The front face of each of the improved building boards is covered with an asphalt composition coating 8 or other similar material which not only serves the purpose of a covering, but also serves the double function of a cement to which a plurality of rectangular face strips 9 of water proof and fire proof material are secured in equally spaced relation to afford transverse strips 10 between the false brick strips 9. The false strips 9 have the lower edges thereof placed substantially flush with the lower edge of the boards 5, with the upper edges of the false bricks spaced a distance below the upper front edge of the board a distance equal to the width of the transverse strips 10, thereby affording a longitudinal strip across the upper front margin of each of the boards 5. The asphalt strips thus formed on the front faces of each of the boards have the appearance of mortar or plaster strips for holding the imitation bricks 9 in place. It will thus be seen that the improved building construction comprises a wooden board having one of the faces thereof treated with an asphalt composition to which false brick strips of roofing material or the like are cemented or otherwise secured.

The improved false brick strips are adapted to be nailed transversely across the front of the building to the risers 4 to form the improved front wall 11 having the appearance of a brick wall. Positioned at intervals in the false brick wall are decorative strips 12 and decorative medallions or blocks 13 of any desired configuration or design. The decorative strips and medallions 12 and 13 are constructed of wood or other suitable material and have the exposed surfaces thereof painted or otherwise covered to have the appearance of stone.

If the old building is of the store type having a store on the first floor the front

of the store may be remodeled to conform with modern store fronts.

It will be noted that the improved building strips may be manufactured in standard lengths and cut on the job to the lengths desired.

It will thus be noted that the improved building strips of this construction having false brick strips cemented thereto by means of asphalt or the like afford a convenient building material whereby the fronts or walls of old buildings may be readily reconstructed at low cost by the improved method herein described so that the walls of the buildings will have the appearance of brick walls including decorative or finishing strips of imitation stone. The improved method and the improved building strips of this invention may not only be used to reconstruct and give old buildings the appearance of new brick buildings, thereby improving the general appearance of the neighborhood, in which the buildings are found, but, if desired, the improved building material may also be used in new construction work as well as in the construction of fences, pillars, posts, and the like.

In the manufacture of the improved building material of this invention it will, of course, be understood that standard roofing or shingle material may be used by cutting the same into strips resembling bricks or into pieces of any desired configuration and then securing said strips or pieces of material to the face of wooden boards by means of asphalt or other suitable cementing material. Any desired color scheme may be used for the strips of material secured to the boards or said strips may be painted a preferred color after the boards have been mounted in place and the wall of the building has been completed.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

A building construction material comprising a strip of wood, a cementitious material coating one face of the said strip, and strips of roofing material narrower than the said strip of wood cemented in spaced edge-wise relation to each other on the wood, each with one of its horizontal edges substantially flush with one of the horizontal edges of the strip of wood.

In testimony whereof I have hereunto subscribed my name at Chicago, Cook County, Illinois.

FRED M. REUTER.
